UNITED STATES PATENT OFFICE.

ALPHONSO H. COBB, OF DETROIT, MICHIGAN.

IMPROVEMENT IN ANCHORS.

Specification forming part of Letters Patent No. **151,276**, dated May 26, 1874; application filed April 11, 1874.

To all whom it may concern:

Be it known that I, ALPHONSO H. COBB, of Detroit, in the county of Wayne and State of Michigan, have invented a new and Improved Anchor, of which the following is a specification:

In the accompanying drawing, Figure 1 represents a top view; Fig. 2, a side elevation, partly in section, on the line *c c*, Fig. 1; and Fig. 3, a diagram of the pivot-connection of arms and shank.

Similar letters of reference indicate corresponding parts.

The invention will first be fully described, and then pointed out in the claim.

In the drawing, A represents the arms, B the flukes, C the shank, and D the stock, of my improved anchor. The flukes B of my anchor are not parallel to the body of the shank, as in the common form of the anchors in use, but are placed in one plane with the arms and stock, which plane is vertical to the body of the shank C. The stock D is the iron one now in common use, capable of being swung parallel to shank, or being detached, if necessary. A wedge-shaped lug or projection, A', is wrought in one piece with arms A, extending centrally between the same, but in a plane vertical to them and parallel to the body of the shank. Its narrower sides taper down to the diameter of the arms, while the angle of its pointed end is, preferably, one of sixty-five degrees. Lug A' is pivoted, by a bolt, *a*, of suitable strength, to the lower recessed end of shank C, bolt *a* being firmly attached by means of its head *a'* and screw-nut *b*. Lug A' swings in the recess *d* of the shank, under an angle of about one hundred and fifty degrees, between two side projections, *d'*, which define the extent of motion of the lug and arms, the inner sides of the same being produced, preferably, under an angle of ten degrees, the lower sides under an angle of seventy-five degrees to the symmetrical axis of the shank, as indicated in Fig. 3. In each position of the arms, whether turned to one side or the other of the shank, the lug A'

comes, by its wedge-shaped end, in contact with the lower side of one projection, *d'*, and the inner side of the opposite projection *d'*, as shown in Fig. 2; and these projections, together with the pivot-bolt, take up the strain when the arms are buried in the ground. The anchor will take hold of the ground into whatever position it may be dropped. If the same falls in the simplest and most common position, with the arms and stock flat to the bottom, the strain of the cable on the stock causes, by the weight of the shank and flukes, the entering of the latter in inclined position into the bottom until the wedge-shaped lug engages the bearing-surfaces of the side projections, as set forth. In the second case, if the anchor were to fall on one fluke, the stock would be perpendicular, and the strain on the cable would draw the stock down flat on the bottom and produce the entering of the arms, as before. Lastly, if the crown were struck, the tautening of the cable would cause the anchor to occupy one of the above-named positions, with the same result.

Besides the increased facility and certainty of the working of the anchor, there is another advantage, that of its easy storage and transportation. The stock can be laid parallel or detached; the arms may be laid parallel, or, by taking out the pin, the parts may be separately stowed or shipped, and afterward joined with but little trouble.

Having thus described my invention, I claim as new and desire to secure by Letters Patent—

The shank C, provided with a recess, *d'*, to receive the lug of the double-fluked arm, the recess having side walls, the inner sides and end walls of which afford bearings for the lug on opposite sides of the pivot, when the flukes are turned to either side, substantially as set forth.

ALPHONSO H. COBB.
